UNITED STATES PATENT OFFICE

ERNEST L. SMITH, OF SAN FRANCISCO, CALIFORNIA, ASSIGNOR TO RINGLETTE PERMANENT COMPANY, OF SAN FRANCISCO, CALIFORNIA, A CORPORATION OF CALIFORNIA

HAIR CURLING APPARATUS

Application filed March 5, 1929. Serial No. 344,256.

This invention relates to electrical hair curling or waving apparatus, and particularly to that type of apparatus set forth in my co-pending application Serial Number 5 286,809.

The principal objects of the present invention are to improve the construction of the curling spindle, whereby the same is precluded from twisting from the hair clamping means; to provide an improved heating element terminal connection whereby short circuits and shocks are eliminated. Other objects are to improve the construction of the hair gripping means in the hair clamping 10 device, and to improve the structure of the hair clamping device.

Additional advantages and objects will appear as the specification proceeds.

With the above mentioned and other objects in view, the invention consists in the novel construction and combination of parts hereinafter described, illustrated in the accompanying drawings and pointed out in the claims hereto appended; it being understood 25 that various changes in the form, proportion, size and minor details of construction within the scope of the claims may be resorted to without departing from the spirit or sacrificing any of the advantages of the invention.

Referring to the drawings, disclosing the invention—

Fig. 1 is a view in top plan of one of the hair clamping devices in closed position.

Fig. 2 is a view in top plan with the complementary clamping bars in open position.

Fig. 3 is a view in end elevation of a curling spindle.

Fig. 4 is a view in side elevation of one of the curling spindles, illustrating the hair end 40 clamp in raised position.

Fig. 5 is a view similar to Fig. 4, illustrating the hair end clamp in plan.

Fig. 6 is a vertical sectional view through one of the curling spindles, with hair wound 45 thereon, and in position in cooperative relation with one of the hair clamping bars; the covering pad being illustrated as embracing the hair.

Fig. 7 is a view in end elevation on line 50 7—7 of Fig. 1.

Fig. 8 is a transverse sectional view on line 8—8 of Fig. 1.

Fig. 9 is a view in enlarged broken detail of one of the curling spindles, illustrating the construction of the heating unit.

In the drawings, referring particularly to Figs. 3 to 5 inclusive, 6 and 9, the numeral 1 indicates an elongated metallic curling spindle provided peripherally of its ends with circumferential holding ratchets 2. The spindle is formed longitudinally with a bore 3, terminating at each end in an enlarged recess 4, in each of which is positioned a disc of insulating material 5, having a central aperture 6. The outer disc faces are set inwardly from the respective ends of the spindle.

Within the bore 3, between the discs 5 the spindle is provided with a tubular porcelain insulator 7, longitudinally of which extends the coiled heating element 8, the terminal ends 9 of which project a short distance through the apertures 6 in the discs 5.

The surface of the spindle 1, between holding ratchets 2, uniformly decreases in its cross-sectional area from its ends toward its center, as clearly illustrated in Figs. 4 and 5. This enables a considerable length of hair to be wound thereon, and at the same time maintains the surface of the hair in a uniform line from end to end of the spindle. On the surface of the spindle is pivotally mounted the hair end clamp 10, of longitudinal and transverse configuration, corresponding to the surface of the curling spindle between the ratchets, this being clearly illustrated in Figs. 4 and 5.

A hair clamp, consisting of the complementary hair clamping bars 11 and 12 hingedly connected at one end by the toggle 13, and provided on opposing longitudinal edges 90 with grooves 14, that in the member 11 being of slightly greater width than that in member 12, is provided to mount a curling spindle in a hereinafter described manner.

Longitudinally of its upper surface, the clamp is formed with a depression 15, arcuate in cross section. The depression is formed half within the upper surface of each complementary clamping bar, and at its ends, the portion of the depression in one bar is re-

cessed to receive the base 16 of a spring arm 17, terminating at its end with a ratchet engaging pawl 18, the pawls of the respective spring members overlying the inner edge of their mounting clamping bar. The free ends of the clamping bars are inwardly slotted and one of them carries a bar locking lever 19 for swinging movement into the slot of the co-operating bar, when the latter are in hair gripping position and the enlarged end 20 of the lever extends to the rear of the bar 12, and thus holds the bars in closed or hair-clamping position.

Positioned within the groove 14 of the lesser width, that in bar 11, is a portion of a tubular elastic hair gripping member 21, the free edge of which is adapted to project, when the bars are in closed position, into the groove 14 of greater width, the present embodiment showing it in bar 12.

With the parts constructed as in the drawings, and as above described, the operator raises from the scalp a lock or portion of hair and while the same is held relatively taut, the bars 11 and 12 are closed on that portion of the lock of hair close to the scalp, as in Fig. 6; the elastic member 21 forcing the hair into the groove 14 of greater width, and thus retaining the same therein; the lever 19 having been moved to locked position. The operator with the hair end clamp of the spindle 1 raised, winds the extreme end portion of the hair lock around the spindle beneath the clamp 10, lowers the clamp and continues the winding operation, with the hair equally distributed longitudinally of the spindle. Such winding will naturally bring the spindle close to the clamping device, and the operator gradually passes the ratchets 2 in the spring arms 17 with the pawl 18 in position to engage the ratchets 2. When in this position, the operator, by any suitable means or tool, imparts a further winding movement to the spindle, drawing the hair lock tightly thereon. When in such position, the operator positions over the spindle a shield or pad, tightly embracing the same, and which, in the present instance, consists of three layers of material, that closest to the lock being felt 22, the next being oil paper 23, and the outside being flexible material, such as tinfoil 24. With the wrapped hair lock thus covered, electrical contacts are made with the terminals 9, causing a heating of the heating element 8, and thus accomplishing the curling or waving operation desired in this particular lock of hair.

If it is desirable, suitable elements 25, such as cork feet or elevating elements may be mounted on the lower surface of the bars 11 and 12 to space the same from the scalp and insure an air circulation between the scalp and the clamping bars.

I claim:—

1. In a hair curling and waving device, a

hair clamp consisting of complementary bars hingedly connected at one end to fold with adjacent side edges in opposing parallel relation, said longitudinal side edges being longitudinally grooved, one groove being of greater width than the other, an elastic hair engaging member tightly held within the groove of lesser width with its free edge adapted for projection into the wider groove and expansion therein, upon folding of the bars to parallel relation.

2. In a hair curling and waving device, a hair clamp consisting of complementary bars connected by toggle hinge at one end to fold with adjacent side edges in opposing parallel relation, said longitudinal side edges being longitudinally grooved, one groove being of greater width than the other, a tubular elastic hair engaging member tightly held within the groove of lesser width with its free edge adapted for projection into the wider groove and expansion therein, upon folding of the bars to parallel relation, and means to lock the bars in said parallel relation.

In testimony whereof I have signed my name to this specification.

ERNEST L. SMITH.
